UNITED STATES PATENT OFFICE.

JACK KLEIN, OF NEW YORK, N. Y.

DESIGN FOR A HANDKERCHIEF.

Application filed October 9, 1923. Serial No. 7,436. Term of patent 7 years.

To all whom it may concern:

Be it known that I, JACK KLEIN, a citizen of the United States, residing in the borough of Manhattan, city, county, and State of New York, have invented a new, original, and ornamental Design for a Handkerchief, of which the following is a specification, reference being had to the accompanying drawing, forming a part thereof.

The drawing shows a plan view of my design.

I claim:—

The ornamental design for a handkerchief substantially as shown.

JACK KLEIN.
